ELECTRICAL SYSTEM FOR PHOTOGRAPHIC COLOR SEPARATION

Maksymilian A. Michalski, Woodside, N.Y., assignor to Berkey Photo, Inc., New York, N.Y.
Filed Oct. 5, 1966, Ser. No. 584,429
5 Claims. (Cl. 315—312)

The present invention relates to an electric system for making photographic direct screen color separations from color transparencies.

In the commonly used methods of preparing color printing plates four color separation negatives or positives must be made for each of the printing plates. The continuous tones of the original must also be converted to halftones which the press can print. There are the two fundamental photographic operations, color separation and screening. Doing both color separation and halftone screening in the same step is called "direct screening" which has been done for many years. However, the long exposure times required for exposing slow films through both a filter and halftone screen and lack of an organized work procedure has discouraged wide use of the system.

Another improvement in the art occurred with the development of a single color correction mask for use with the transparency to make the four separation negatives thus replacing the multiple masks heretofore used. In producing the color correction mask a single exposure records each of the necessary photographic mask images in a different layer of the same piece of film. During processing these mask images are changed to color dye images. In preparing separation negatives, the finished single color correction masking film is registered with the original transparency from which it was made. Separation filters are used to select automatically the correct mask image. This mask image, in turn, corrects the separation negative that is being exposed. By the use of the single masking film the separation procedure is essentially fixed. Further, the development of efficient enlargers with high intensity light sources and faster film has reduced the long exposure times heretofore required. However, the steps involved must be carried out in total darkness and thus the chances of making errors are multiplied.

The present invention aims to overcome the difficulties by providing an electrical circuit for electrically programming the operations required in producing color separation negatives from color transparencies.

In accordance with the invention this is accomplished by providing a main exposure lamp, a flash panel, an electrical circuit, and timed switching means for energizing the lamps in accordance with settings for exposures of predetermined lengths.

Another object of the invention is to provide an electrical system which is simple and economical in manufacture, efficient in operation, and durable in use.

Other objects and advantages of the invention will be apparent from the following description and from the accompanying drawing which shows, by way of example, an embodiment of the invention.

In making separation negatives using the direct screen system the separation procedure is standardized for all acceptable transparencies. The tone reproduction requirements in this system are not related to the density range of the transparencies. It has been determined that in reproducing any transparency with this system the most important consideration is to achieve the proper tone rendering from highlights through upper middle tones which is quite independent of the tone rendering of the total range of the transparency.

Different shop conditions and transparencies require

2

use of a trial method to produce the first satisfactory control negative with acceptable highlight dot size for a particular condition. However, once these exposures are established they remain constant and will be equal for all later transparencies. The first set of negatives is produced from a table which contains recommended exposure times for the four different color separations. The first set of negatives is examined and if necessary one or more new sets of negatives are made until a satisfactory set of control negatives is made. The exposure times and lens opening number of the satisfactory separation negatives are recorded and used to set exposures as hereinafter described. In making these separation negatives, after the main exposure, each separation negative with the exception of the black negative is given a flash exposure with the screen in position. The length of flash exposure is determined initially and does not change thereafter with the nature of the transparency.

Thereafter, in making color separation negatives from other transparencies, it is only necessary to measure the highlight density which varies from one transparency to another, the recorded exposure times remaining the same provided the lens opening is adjusted depending upon the highlight of the particular negative.

The apparatus to make the separation negatives includes a graphic arts enlarger with a registration system for the color correction mask and transparency. Preferably the enlarger is adjustably mounted on a column above a vacuum easel type on an enlarging table. Suitable screens may be placed in registration for each color separation over the separation film on the easel. Mounted on the enlarging table is a flash panel adapted to be swung over the separation film for a flash exposure. Exposure control and switching means is contained in a console type programming unit conveniently mounted for manipulation by the operator while in position before the enlarging table.

The programming unit includes a timing unit, means for setting the timing unit for exposures of varying lengths for both the main and flash exposures and switching means for control of room light, vacuum system for the vacuum easel, filter wheel control means, and a light meter.

In making color separation negatives using the electric system in accordance with the invention, the color correction mask is exposed in a conventional manner in a contact printing frame or the negative carrier of the enlarger. The developed mask is registered over the transparency and placed in the transparency holder of the enlarger. The image is projected to the desired size and focused on the vacuum easel while the room light is switched off. A focusing switch when pressed actuates the main light source which is used for focusing and sizing of the projected image, the filter wheel being automatically positioned so that there is no filter before the lens.

The timing units for each of the color separations are set for both main and flash exposures according to the recorded values obtained in making the control negatives. The light meter control dials are set to the values obtained in making the control negatives.

The light meter probe is positioned in the highlight area of the projected image on the easel, and the aperture of the lens adjusted to produce the same reference reading on the meter as obtained with the control negative. Thereby the light intensity is proportional to that obtained for the control negative and permits the use of the same timing cycles to obtain the same quantity of light for the exposure.

Referring to the drawing an on-off switch 1 applies power to the system. In order to focus and size the image, room light 2 is switched off by switch 3, main exposure

lamp 4 is turned on by closing switch 5. The main exposure lamp 4 is preferably a pulsed xenon discharge lamp. Blower 6 and enlarger power lift 7 are continuously energized. The on-off switch 1 is supplied from a source of alternating current indicated by power supply 8.

A timing range for the main exposure can be set between 0 and 330 seconds by the use of series connected timing selector switches 10 and 11. Timing selector switch 10 switches ten resistors 12 and covers the range from 0 to 10 seconds in steps of one second. Timing selector switch 11 switches ten resistors 13 and covers the range from zero to 100 seconds in steps of ten seconds. A multiplier switch 16 permits extension of these ranges by factors of two or three so that a total time of 330 seconds may be had.

A flash panel 17 is controlled to produce a timing range for the flash exposure between 0 and 22 seconds by the use of a twenty-three position selector switch 14 switching series connected resistors 15. The flash panel 17 is preferably a luminescent panel, although alternative constructions may be used which present a surface uniformly emitting light.

Separate timing ranges are provided for each separation color, that is, for cyan, magenta, yellow, and black, the timing selector switches for cyan identified as 10, 11, and 14, for magenta 10m, 11m, and 14m, for yellow 10y, 11y and 14y, and for black 10b, 11b and 14b. The timing selector switches are set at the recorded values obtained from the data of the control negatives.

Light meter probe 20 is positioned in the highlight area of the projected image on the easel, the light meter is energized by switch 21. Coarse range light meter selector switch 22 and fine range potentiometer 23 are set to the recorded values heretofore obtained. The lens aperture of the enlarger is adjusted so that meter 24 produces the same reference reading as heretofore.

The system is now in readiness for the making of the four color separation negatives.

Cyan position switch 25 is actuated and through a mechanical interlock focus switch 5 is opened. Switch 25 is mechanically coupled with switches 26 and 27 so that all three switches are actuated together. Double pole switch 26 connects timing selector switches 10, 11 and 14 to a common bus 18. Switch 25 has two sets of contacts 25a and 25b. Contact 25a completes the circuit of filter wheel motor 28 through normally closed contacts 29 of a filter wheel automatic advance relay 30 and contact 31 of filter wheel commutator switch 32 which causes commutator switch 32 to proceed and open at cyan #1 position (switch 31 open). Simultaneously a cyan #1 filter is positioned under the enlarger lens. Closed contact 25b connects coil 34 of relay 30 to open contact 35 of switch 36 of timing reset relay 37, and to swinger 40 in normally open position.

A screen is registered with the film to be exposed and the film is placed on the easel. The easel is equipped with vacuum channels controlled by valves actuated by solenoids 41, each of which are controlled by double throw single pole switches 42 which can be thrown to screen or film position. A relay 43 operates contact 44, the selected solenoids 41 and vacuum pump 45 when energized through switch 46 closed to one of contacts 47, 48 or 49 respectively providing film, screen and overlay positions. The film is held in position on the easel by the vacuum.

Main exposure switch 50 is closed momentarily which energizes capacitor reversal and timing interlock relay 51. Power is applied to the main exposure lamp 4 through the closed contacts of switch 36. Simultaneously, as will be described later, timing unit 52 is actuated. Relay 51 is self interlocked through its contacts 53. At the expiration of the timed interval as set on selector switches 10 and 11 switch 36 is momentarily dropped to its contact 35 opening the circuit to the main exposure lamp 4 and terminating the exposure. While switch 36

is making momentary contact with contact 35 relay 34 is energized and interlocked through switch 40 until contact 54 of filter wheel commutator switch 32 is opened thereby stopping the filter wheel in cyan #2 position.

5 The screen, already in register, is placed over the film and switch 46 is turned to contact 48 (screen) to hold the screen in position. Switch 50 is momentarily closed so that the film is exposed for the preset interval by main exposure lamp 4.

10 The flash panel is swung into position and switch 55 actuated. Switch 55 includes normally closed contact 56 and normally open contact 57. Contact 56 is opened momentarily when switch 55 is actuated to prevent possible misfiring of the timing circuit. Contact 57 is closed to apply power to the coil of flash interlock and control relay 58.

15 The relay 58 activates normally closed switch 59 which when opened disconnects capacitors from the timing circuit, also a normally open switch 60 which is closed to energize and interlock timing relay 51 to start a flash timed interval. Relay 58 also actuates a double throw switch 61 having contacts 62 and 63. Normally closed contact 62 connects the selector switches 10 and 11 to the timing unit 52 for main exposure. Contact 63 connects selector switch 14 to the timing unit 52 for flash exposure. Relay 58 further activates a double throw switch 64 having normally closed contact 65 and normally open contact 66. Closed contact 65 connects through a normally open switch 68 actuated by the relay 51 to complete a power supply to the main exposure lamp 4. Normally open contact 66 provides an interlock for relay 58 through switch 36 and also applies power to the flash panel during the flash exposure cycle.

20 The timing circuit 52 is described and claimed in my co-pending patent application Ser. No. 581,032, filed Sept. 21, 1966, and titled Timing Circuit. The circuit is based on the discharge of capacitors at the start of a timed interval to a charge of the reverse polarity of a magnitude, when amplified, to trigger controlled rectifier 70 into conduction, so that relay 37 is actuated opening normally closed switch 36, and thus deenergizing the interlock circuits of timing relay 51 in the case of a main exposure, and deenergizing relays 58 and 51 in the case of a flash exposure.

25 The timing circuit 52 is supplied by a transformer 71 providing direct current by a diode 72 which is filtered by a capacitor 74 and a resistor 75. A zener diode 76 regulates the direct current voltage. A voltage divider 77 provides a voltage of one magnitude to negatively charge capacitor 79. Additional capacitors 80 and 81 may be switched in parallel with capacitor 79 if desired by switch 40. Transistor 85 is adapted to be turned on by a slight positive potential on its base received through diode 86 from capacitor 79. A negative bias is provided for the control electrode of controlled rectifier 70 by a voltage divider 87 receiving a controlled negative potential filtered by resistor 89 and capacitor 90 and controlled by zener 91. The timing circuit condition so far described is that present at the start of a timing cycle.

30 A timing cycle is started by energization of timing relay 51 which operates switches 93 and 94 so that the capacitor 79 is discharged against the potential of voltage divider 95 and charged in the reverse direction with a positive going potential. As capacitor 79 becomes positive a diode 86 passes current and transistor 85 is turned on with an amplifying action and a positive potential is produced on the top of stabilizing capacitor 96 to trigger the gate of controlled rectifier 70.

35 The operation of the electric system will now be explained in somewhat different language in order to bring out more clearly the novel features of the invention.

The electric system includes switching means to connect the exposure lamp 4 to the source of power 8 to provide a timed exposure measured by the timer 52. The exposure is started by closing starting switch 50 which causes to be energized a timing relay 51 controlled by

the switch 50. Main lamp switching means 68 is controlled by the timing relay 51 to energize the lamp 4. The timing relay 51 is provided with interlock switching means 53 and also timer switching means 93 and 94 for starting the timer 52. It will be remembered that the operation of the timer 52 is predicated on the charge of the capacitor 79 to one potential, the capacitor being reversed in its connection to a somewhat different potential by the switching means 93 and 94 for a charge in the reverse direction, the time interval depending upon the time for the capacitor 79 to be charged in the reverse direction. A further control of the time of charge of the capacitor 79 in the opposite direction is provided by the resistors of main exposure control means 10 and 11. The timing reset relay 37 is operable by the timer 52 at the expiration of the predetermined operating time as determined by main exposure control means 10 and 11. Normally closed switching means 36 controlled by the timing reset relay 37 is operative to deenergize the timing relay 51 and thereby deenergize the main lamp 4 from the source of power 8.

The next operation requires the flash panel 17 to be actuated for a predetermined length of time from the source of power 8. Operation is started by actuating the flash panel starting switch 56. Flash panel exposure control means 14 has already been set to determine the time of operation of the timer 52. The flash control relay 58 is operated by the flash panel starting switch 56. The flash relay 58 controls double throw switching means 64 which is normally closed against contact 65 so as to provide a series circuit for energizing main lamp 4. When the flash relay 58 is operated to its other position contact 66 energizes the flash relay contact and simultaneously energizes the flash panel 17. The other double throw switching means 61 of flash relay 58 is normally closed to contact 62 connecting the main exposure means 10 and 11 to the timer 52, but when the flash relay 58 is operated the double throw switch engages contact 61 in its other position thereby connecting the flash panel exposure control means to the timer 52 for the timed operation of the flash panel.

While the invention has been described and illustrated with reference to specific embodiments thereof, it will be understood that other embodiments may be resorted to without departing from the invention. Therefore the form of the invention set out above should be considered as illustrative and not as limiting the scope of the following claims.

I claim:

1. An electric system comprising a main exposure

45

50

40

35

30

25

20

15

10

5

lamp, a source of power, a timer, a main exposure starting switch, a timing relay controlled by the main exposure starting switch, main lamp switching means controlled by said timing relay for energizing said main exposure lamp from said source of power, interlock switching means for said timing relay, timer switching means controlled by said timer relay for starting the timer, main exposure control means for said timer adjustable to set the operating time thereof, a timing reset relay operable by said timer at the expiration of the operating time thereof as determined by said main exposure control means, normally closed switching means controlled by said timing reset relay operative to deenergize said timing relay and thereby deenergize said main lamp from said source of power, a flash panel, a flash panel starting switch, flash panel exposure control means for said timer adjustable to set the operating time thereof, a flash control relay operative by said flash panel starting switch, a flash relay interlock circuit, double throw switching means controlled by said flash relay normally in one position in series with said circuit for energizing said main lamp and in its other position opening the circuit for energizing said main lamp and energizing said flash relay interlock circuit and said flash panel, and double throw switching means controlled by said flash relay normally in one position connecting said main exposure control means to said timer and in its other position connecting said flash panel exposure control means to said timer.

2. An electric system according to claim 1 in which the main exposure lamp is a pulsed xenon discharge lamp.

3. An electric system according to claim 1 in which the flash panel is a luminescent panel.

4. An electric system according to claim 1 in which the main exposure control means is a plurality of resistors series connected and a selector switch is provided to switch in resistors as desired.

5. An electric system according to claim 1 in which the flash panel exposure means is a plurality of resistors series connected and a selector switch is provided to switch in resistors as desired.
